UNITED STATES PATENT OFFICE

DONALD E. ROBERTS, OF MILWAUKEE, WISCONSIN

APPLICATOR FOR CONDUCTING ULTRA-VIOLET RAYS

Application filed January 31, 1929. Serial No. 338,445.

The invention relates to applicators for conducting ultra-violet rays, which use quartz as a conducting material, and are comprised of a multiplicity of quartz segments; 5 such segments being housed within a rubber tube. The objects of the invention are, first, to provide an efficient and safe method to join the segments, and, second, to reduce as little as possible the useful diameter of the 10 assembled applicator.

One form of the invention is illustrated in the accompanying drawing, in which Figure 1 is a view of the assembled applicator; Fig. 2, is a cross section of the assembled applicator with some quartz segments removed for the purpose of simplicity of illustration; 15 Fig. 3, is a cross section of the applicator through XX, Fig. 1; and Fig. 4, is a view of a quartz center segment as at 2, 2, 2, 2, Fig. 20 1, and 2, Fig. 2.

The applicator for conducting ultra-violet rays as covered by this invention consists of a quartz base segment 1, Fig. 1, and 1, Fig. 2, and a multiplicity of quartz center segments, 25 2, 2, 2, 2, Fig. 1, and 2, Fig. 2, and a formed quartz tip segment 4, Fig. 1, and 4, Fig. 2, and a friction clamp made of spring metal as shown at 5, Fig. 1, and 5, Fig. 2, and 5, Fig. 3, and a #30 Browne and Sharpe gauge silver 30 wire shown at 6, Fig. 1, and 6, Fig. 2, and 6, Fig. 3.

Figure 2, shows how each quartz segment is drilled through the center; the formed tip segment 4, Fig. 1, and 4, Fig. 2, having a 35 transverse and two diagonal holes as shown at 4, Fig. 2; the base segment 1, Fig. 1, and 1, Fig. 2, being drilled so that the hole has its outlet so that the wire 6, Fig. 1, and 6, Fig. 2, and 6, Fig. 3, may be placed under friction clamp 5, Fig. 1, and 5, Fig. 2, and 5, Fig. 3.

Figure 3, shows method of holding wires 6, Fig. 1, and 6, Fig. 2, and 6, Fig. 3, under friction clamp 5, Fig. 1, and 5, Fig. 2, and 5, Fig. 3.

Figure 4, shows a quartz center segment as at 2, 2, 2, 2, Fig. 1, and 2, Fig. 2, with one end dome shaped and the other end cupped shaped and each end polished so as to pass 50 ultra-violet rays more efficiently.

One end of the base segment 1, Fig. 1, and 1, Fig. 2, is flat and polished, and the opposite end is dome shaped and polished.

The base end of the quartz tip segment at 4, Fig. 1, and 4, Fig. 2, is cup shaped and 55 polished.

The length of the applicator may be changed by the addition or subtraction of quartz center segments as at 2, 2, 2, 2, Fig. 1, and 2, Fig. 2.

Due to the segments being strung on the flexible silver wire, and the slight ball and socket joint action of the segments made possible by the ends of the segments being domed and cupped, the applicator when assembled 60 is slightly flexible.

Due to the property of quartz as a conductor of ultra-violet rays even when placed at an angle adjacent to another piece of quartz, ultra-violet rays are conducted by 70 this applicator with but a slight loss of efficiency even when the applicator is slightly bent.

The spring metal friction clamp shown at 5, Fig. 1, and 5, Fig. 2, and at 5, Fig. 3, is 75 fastened to the base segment 1, Fig. 1, and 1, Fig. 2, with cement.

The method of assembling the applicator is as follows: The silver wire is first placed through the transverse hole in segment 4, Fig. 1, and 4, Fig. 2, and then each end of the wire is put through the diagonal hole to which it is nearest. Then the small center segments are strung on the wires like beads and then the two ends of the wires are put 80 through the hole in the base segment 1, Fig. 1, and 1, Fig. 2, and the wire is stretched taut to bring all segments in firm contact and then the ends of the wires are slid under the friction clamp in order to keep the wires taut 85 while the applicator is in use.

The applicator may easily be taken apart for sterilization of the parts by removing the wire from the friction clamp and separating the segments.

I am aware that prior to my invention, applicators for conducting ultra-violet rays have been made of a multiplicity of quartz segments and with formed tips, but such applicators when assembled, being held to- 95 100

gether with but a rubber tube, have no pre-caution to prevent the segments being lost while within a sinus while the applicator is in use, and in such applicators, the rubber tube used to hold the segments together takes up 5 extremely valuable space. I make no claim to any method of manufacturing such applicators, nor, in a broad way, applicators comprised of a multiplicity of quartz segments.

- 10 I claim:
- 10 An applicator for conducting ultra-violet rays comprised of a multiplicity of polished quartz segments, having the segments fastened together by means of a wire which passes transversely through the tip segment, 15 then diagonally through the tip segment to the base of the tip segment and then piercing the center of each center segment and then through the center of the base segment and out the side of the base segment through a 20 diagonal hole and fastened in place under a friction clamp in the manner described; such applicator being slightly flexible and adjustable as to length.

DONALD E. ROBERTS.
